UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

DESIGN FOR A FUSE BOX

Application filed April 3, 1929. Serial No. 30,726. Term of patent 14 years.

To all whom it may concern:

Be it known that I, ALWIN G. STEINMAYER, a citizen of the United States, residing at Milwaukee, in the county of Milwaukee and State of Wisconsin, have invented a new, original and ornamental Design for Fuse Boxes, of which the following is a specification, reference being had to the accompanying drawing, forming part thereof.

Figure 1 is a perspective view of a fuse box, showing my new design; and

Figure 2 is a perspective view illustrating the opposite side of the fuse box.

I claim:

The ornamental design for a fuse box, as shown.

ALWIN G. STEINMAYER.
